[57] ABSTRACT

A machine for breaking up and removing compacted snow and ice utilizing a number of narrow disks placed side by side. The disks are mounted in pairs, each pair consisting of a breaker disk and a sweeper or pick up disk, individually spring-pressed downward. The breaker disks are designed to crush the snow or ice remaining on a road after plowing, and force the crushed snow or ice sideward, where it is picked up by the sweeper disks. A shoe immediately behind the disk assembly guides the snow onto a conveyor belt which ejects the snow toward the side of the road. The machine is mounted on, or towed by, a truck or other vehicle.

ICE AND SNOW REMOVAL MACHINE

This invention relates to machines for removing snow and ice from roads, runways, and similar surfaces, and more particularly to a machine for removing the residual compacted snow and ice which cannot be removed by a snow plow.

BACKGROUND OF THE INVENTION

The usual straight snow plow blade, or revolving helical blade, is a rigid piece extending from one side to the other of the plowing vehicle. The blade has to be set higher than the road surface, to avoid striking irregularities in the surface and damaging the surface or the blade. The more irregular the surface the higher the plow blade has to be set. The residual layer of snow which remains on the road after plowing is likely to become compacted or turn into ice, creating a hazardous condition. This is usually dealt with by salting or sanding, a measure which is expensive for large areas and causes damage to the road surface and to vehicles traveling on the road.

The principal object of this invention is to provide a machine which will penetrate and break up a layer of compacted snow or ice and completely remove it down to the surface of a road, without danger of damage to the road surface or the machine itself. Another object is to provide a machine which automatically conforms to an irregular surface or to a road of crown construction. Another object is to provide a machine which is simple to construct and maintain, which can be used on the usual types of snow removal vehicles, and which eliminates the expense of sanding and salting. Other objects, advantages, and novel features will be apparent from the following description.

SUMMARY

The machine here described utilizes a breaker and pick up assembly made up of a number of narrow disks mounted side by side and close together. Alternate ones of the disks are breaker disks and the others are sweeper, or pick up disks. The disks are mounted in pairs, each pair consisting of a breaker disk and a pick up disk. Each pair is individually spring-pressed downward so that the assembly will accommodate itself to an irregular surface. Immediately behind the breaker assembly is a sloping shoe leading to a conveyor belt which runs transversely along the assembly and carries the swept up snow to one side. A baffle is mounted behind the belt to keep the snow from falling off at the rear. The machine may be mounted on, or towed by, a truck, tractor, or other snow removal vehicle, and the breaker assembly may be made up in various widths according to the width of the vehicle with which it is to be used.

DESCRIPTION OF THE DRAWINGS

In the drawings illustrating the invention:

FIG. 1 is a top plan view, partly broken away, of an ice and snow removal machine constructed according to the invention;

FIG. 2 is a rear view of the machine, with the baffle omitted for clarity;

FIG. 3 is a side elevation of the machine;

FIG. 4 is a cross-section taken along line 4 — 4 of FIG. 3;

FIG. 5 is a perspective view of an arm which supports a pair of the disks;

FIG. 6 is a side elevation of a modified form of the disk support and drive assembly;

FIG. 7 is an enlarged fragmentary view taken in the region of the sweeper disk of FIG. 6, with the breaker disk removed;

FIG. 8 is a cross-section taken along line 8 — 8 of FIG. 7;

FIG. 9 is a fragmentary view similar to FIG. 7 illustrating another modification of the disk drive assembly;

FIG. 10 is a cross-section taken along line 10 — 10 of FIG. 9;

FIG. 11 is an enlarged fragmentary elevation illustrating a modification of the breaker disk assembly;

FIG. 12 is a cross-section taken along line 12 — 12 of FIG. 11;

FIGS. 13, 14, and 15 illustrate variations of the tread of the sweeper disks; and

FIG. 16 illustrates a variation of the breaker disk assembly.

DESCRIPTION OF THE PREFERRED EMBODIMENT

As shown in FIGS. 1 through 5, the parts of the machine are mounted on a rectangular framework made up of bars 20, 21, 22, and 23, and a cross-bar 24. It is understood that the framework is intended to be attached to a vehicle, for example, mounted on the rear of a truck which may carry an ordinary plow in front for removing deep snow, or towed by a vehicle. The machine may be weighted, if necessary, in any suitable way, to produce the downward pressure required by the entire breaker assembly. A pair of vertical bars 25 and 26 support a drive shaft 27, which may be driven in any convenient manner, for example, by a belt and pulley 28, from the motor of the vehicle itself or a separate motor.

A number of gears 29 are secured to shaft 27 and driven by it. These gears mesh with gear tooth faced sweeper disks 30. The vehicle moves in the direction of arrow 31 in FIG. 3, and gears 29 are driven in the direction of arrows 32, driving the sweeper disks 30 in the direction of arrow 33. Shaft 27 may be supported at intervals by braces 34, if required by the width of the assembly. These are mounted on a baffle 35 which extends transversely across the rear of the machine and is supported by bars 36 and 37 extending downward from the framework. A conveyor belt 38 is mounted in front of the baffle, and driven by any suitable means (not shown) in the direction of arrows 39 in FIG. 2, assuming that the snow is to be discharged to the right side of the road. In a situation where left hand discharge of the snow is desired, the direction of the conveyor drive can be reversed.

A number of arms 41 are rotatably mounted on shaft 27. These arms support the sweeper disks 30, and breaker disks 42, a sweeper disk and a breaker disk being mounted on each arm. The arms are rotatable on shaft 27 independently of one another, so that each pair of breaker and sweeper disks is independently movable up and down. The whole breaker and sweeper disk assembly can be set very close to the surface which is to be cleaned of impacted snow and ice, without danger of damaging the surface or the machine.

The detailed construction of an arm 41 is illustrated in FIGS. 3, 4 and 5. The arm has an upwardly extending rod portion 41a which is received in a spring-pressed shock absorber unit 43 mounted on bar 24. A pin 41b

serves as a shaft on which disk 30 is rotatably mounted. Disk 30 has an indented portion 30a in which an offset portion 41c of arm 41 is received. This offset portion carries a pin 41d on which the breaker disk 42 is rotatably mounted.

The breaker and sweeper rolls are of a width in the order of one to two inches. When the machine is in operation, the breaker rolls crush the residual compacted snow and ice, and the sweeper rolls throw it back onto the conveyor belt, which carries it to the side of the road. The individual mounting of the pairs of breaker and sweeper disks allows the whole assembly to be set very close to the road, or other surface to be swept, without danger of damage to the surface or the machine.

FIG. 6 illustrates a variation of the machine in which the framework, generally indicated by the numeral 45, supports, as in the previous example, a baffle 35, a conveyor 38, and a shoe 40. The framework also supports a number of brackets 46 and a drive shaft 47, which is driven by any suitable means and drives a belt and pulley 49. An arm 48, for supporting a pair of breaker and sweeper disks, is rotatably mounted on shaft 47. The arm 48 is connected by a link 51 to a hydraulic unit 52 mounted on the framework and adapted to apply yielding downward pressure to the arm. The arm supports a sweeper wheel assembly, generally indicated by the numeral 54. The arm is attached to a stationary disk 55 around which an internally gear toothed ring 56 revolves. Ring 56 meshes with a gear 50 driven by the drive 49. The ring carries brush elements 57 set into its outer surface. Alongside the sweeper wheel assembly is mounted a breaker disk 58. The position of the breaker disk is shown in FIG. 7 by the dot and dash line 58a.

Stationary disk 55 has an elongated vertical slot 59, in which a slide 60 is mounted. The slide is secured by a back plate 61. Disk 58 has a shaft portion 58b which is rotatably mounted in a bearing 62 in slide 60. The slide carries a lug 60a which is engaged by a piston rod 63 driven by a hydraulic cylinder 64. A second lug 60b on the slide engages a stop 65 mounted on disk 55. Piston 63 is shown in extended position in FIGS. 7 and 8. By retracting the piston, slide 60 can be moved downward with respect to disk 55. In the extreme down position, a lock member 67 is moved in by a cylinder 66 to engage over lug 60b and lock the slide in place. When the slide is moved down, disk 58 is moved down with respect to disk 55 and ring 56, raising the sweeper assembly above the level of the road surface 68. Under certain conditions, for example when the snow removal vehicle is being driven rapidly on a highway which has been largely cleared, the breaker disks alone may serve to break up the residual snow and ice and throw it onto the belt.

FIGS. 9 and 10 illustrate an alternative way of driving the sweeper ring 56. A breaker disk 69 has a shaft portion 69a rotatably mounted in bearing 62 on slide 55. Disk 69 has an internally toothed surface 69b which meshes with a gear 70 mounted on a shaft 72 on disk 55 and rotatable on the shaft. Gear 70 carries another gear 71 which meshes with the toothed surface of ring 56. The ring is thus driven by the rolling motion of disk 69 as the vehicle moves along the road surface.

FIGS. 11 and 12 illustrate a breaker disk assembly made up of several breaker units, and also a sweeper disk equipped with a mechanism for ejecting the snow picked up. A stationary disk 75 carries an offset arm

portion 75a which extends upward and is linked to a hydraulic or spring pressure unit 76. A sweeper ring assembly 77 is rotatably mounted on disk 75. A number of L-shaped ejector units are slidably mounted in ring 77. Disk 75 has a flange 75a, the edge of which engages the ejector units 78 along the sides and upper part of the ring and holds them out in the ring. At the bottom of the assembly, the flange has a slot 79 in which the lugs 78a of the ejector units ride as they pass around the bottom of the assembly. The units are thus raised as they approach the road surface, allowing snow to enter the cavities 80 in which the units are mounted. As the units rise from the road surface, they are driven outward by the edge of flange 75b so that they eject the snow picked up.

Disk 75 carries a pair of studs 81 on which ball bearings 82 are mounted. The bearings are in rolling contact with a ring 83 which is part of the breaker assembly. At the bottom, disk 75 carries a shaft 75c on which ball bearings 84, 85, and 86 are mounted. Bearing 85 engages the inner surface of ring 83, so that the ring has three point rolling suspension. Disks 87 and 88 are mounted on bearings 84 and 86, respectively. The disks and ring 83 together serve as a breaker disk assembly.

FIGS. 13, 14, and 15 show portions of the rims of sweeper disks 90, 91, and 92, respectively, having various treads. Disk 90 has central recesses 93 in its rim. Disk 91 has recesses 94 along the edges of its rim. Disk 92 has a raised serpentine tread 95 on its rim.

FIG. 16 illustrates a breaker disk assembly similar to that of FIGS. 11 and 12, composed of a central ring 96 having a double bevelled rim 96a, and a pair of disks 97 and 98 having right and left hand bevelled rims, so that the broken up ice and snow is directed sideward from under the assembly.

In all the variations of the machine here described, the breaker disks, or breaker disk assemblies as the case may be, are relatively narrow, on the order of 1 to 2 inches. The sweeper disks are likewise narrow to allow close spacing of the breaker disks. The individual mounting of the pairs of disks allows the entire assembly to accommodate itself to the contour of the road surface, and also allows the disks to penetrate to the surface in uneven spots so that there are no patches of compacted snow or ice left on the surface to cause hazardous driving conditions. The use of this machine eliminates the need for salting or sanding the surface. When the machine is used on a vehicle which has a primary removal device, such as a plow, snow can be removed completely from the road surface in one pass.

In the case of the breaker disk of FIG. 16, the ring 96 and disks 97 and 98 may be faced with rubber thick enough and compressible enough so that their rims flatten out under pressure creating a sidewise force which ejects the snow to the side.

What is claimed is:

1. An ice and snow removal machine: an assembly of rotatable disks mounted in pairs in close side by side arrangement, each pair being independently movable up and down, one disk of each pair being a breaker disk with a rim configuration adapted to break compacted ice and snow, and the other disk of each pair being a sweeper disk with a rim configuration adapted to sweep up loose ice and snow; means for yieldably urging each pair downward; and means for driving said sweeper disks with a rotary motion.

2. An ice and snow removal machine as described in claim 1, said machine including a drive shaft, a number of arms rotatably mounted on said drive shaft, each of said pairs being mounted on one of said arms, and a number of gears secured to said shaft and constituting said means for driving said sweeper disks, said sweeper disks having toothed rims meshing with said gears.

3. An ice and snow removal machine as described in claim 1, said machine including a shaft, a number of arms rotatably mounted on said shaft, each sweeper disk comprising an internal disk fixed to one of said arms and a rotatable ring surrounding said internal disk, the breaker disk of each pair being rotatably mounted on the internal disk and vertically slideable thereon, and each pair including means for selectively positioning its breaker disk with respect to its sweeper disk.

4. An ice and snow removal machine as described in claim 1, each of said breaker disks comprising a plural-

ity of individually rotatable members.

5. An ice and snow removal machine as described in claim 1, each of said sweeper disks having brush members mounted in its rim.

6. An ice and snow removal machine as described in claim 1, each of said sweeper disks having a rim provided with recesses and snow ejection members movably mounted in said recesses and means for driving said members in and out of said recesses.

7. An ice and snow removal machine as described in claim 1, each of said sweeper disks having a rim provided with raised and recessed portions.

8. An ice and snow removal machine as described in claim 1, having a shoe partially underlying said assembly, a conveyor belt disposed along said shoe and laterally movable along said assembly, and a baffle extending laterally of said assembly alongside said belt.
